GRAB HOIST

John Russell Taylor, Bedford, England, assignor
to Cutler-Hammer, Inc., Milwaukee, Wis., a
corporation of Delaware

Application March 18, 1939, Serial No. 262,651
In Great Britain March 21, 1938

5 Claims. (Cl. 212—81)

This invention relates to grab hoists.

Grab hoists are known having two separate lines, viz. a holding line and a closing line, actuated by respective electric motors, the closing line, when in tension, closing the grab, and both lines, when in tension, operating to support the weight of the grab. When the grab is to be supported in an open condition the holding line must take the whole weight, the closing line remaining slack, but when the full grab is to be supported, the closing line must be tight to keep the grab closed and it serves to share the load with the holding line which is also tight.

The object of the invention is the provision of an improved grab hoist of this kind in which inter alia it will be easier to maintain the grab open or closed at all speeds and especially at low speeds where difficulty has been heretofore experienced, and in which the control in general will be more smooth. The invention consists in the arrangement that the two motors are direct current motors fed from respective generators.

In order that the invention may be the more clearly understood a grab hoist in accordance therewith will now be described, reference being made to the accompanying drawings wherein:

Figure 1 is an across-the-line diagram of the power circuits of the holding motor;

Fig. 2 is a similar diagram of the power circuits for the closing motor;

Fig. 3 is an across-the-line diagram of a drum controller and its associated control circuits for controlling the power circuits of the holding motor;

Fig. 4 is an across-the-line diagram of a drum controller and its associated control circuits for controlling the power circuits of the closing motor;

Fig. 3a is a representation of the switches embodied in Figs. 1 and 3 with their coils and contact members disposed in horizontal alinement with their positions in the across-the-line diagrams;

Fig. 4a is a diagram similar to that shown in Fig. 3a of the switches embodied in Figs. 2 and 4, and

Fig. 5 is a schematic view illustrating the apparatus shown in Figs. 1 to 4 in connection with a grab bucket having a holding line and a closing line.

As shown in Fig. 5, two separate winches are employed for the holding line and the closing line respectively and said winches are driven by direct current electric motors M₁ (Figure 1) and M₂ (Figure 2) respectively. The motors M₁ and M₂

have independently excited fields M_{F1} and M_{F2} and their armatures are connected in circuit with the armatures of respective generators G₁ and G₂. The generators also have independently excited fields G_{F1} and G_{F2}. The field and armature circuits of the two motor generator sets are identical. The speed and direction of each motor is determined primarily by the degree and direction of field excitation of the generator supplying it, and each motor, after it has received maximum armature current from its generator, is capable of being speeded up a final step by having a resistance section r₁ inserted in its field circuit.

The two motor generator sets are controlled by means of respective small drum controllers D₁ (Figure 3) and D₂ (Figure 4), and these drum controllers are identical except that the final step of speed can be applied only in the hoist direction in the case of the holding line drum D₁, and only in the lowering direction in the case of the closing line drum D₂.

More particularly, in the off position (illustrated) of the holding line drum D₁, a main switch has its winding w₁ energised and its contact 1c₁ closed, connecting the armature G₁ of the holding line generator in circuit with the armature M₁ of the holding line motor. The energising circuit for said winding w₁ may be traced from line L₁, drum contact 1, drum contact 2, contacts c₂ of overload relay w₂, said winding w₁, normally closed interlock 2c₁ on the main switch winding w₁ to line L₂. This main switch upon closing, establishes a maintaining circuit for its winding w₁, through normally open interlock 3c₁ which remains established at all the positions of the drum and can only be disestablished upon the occurrence of overload whereupon the overload winding w₂ opens the contacts c₂. The original energising circuit of said main switch is, however, only established, through drum contact 2, at the off position of the drum, so that, overload having occurred, the main switch can only be re-energised by returning the drum to the off position. When main switch winding w₁ is energised, interlock 2c₁ opens, thereby throwing an economising resistance r₂ into the circuit.

At the first hoisting notch h₁ of said holding line drum, a hoist switch has its winding w₃ energised through drum contact 3, and its contacts 1c₃ closed thereby effecting energisation of the generator field G_{F1} through all of a number of sections of a resistance R, in the hoisting direction. Upon response of said hoist switch an auxiliary contact 2c₃ thereon closes, thereby establishing two circuits in parallel with said ener-

gising circuit of the hoist switch winding w_3 , one of said circuits energising the winding w_4 of a normally open decelerating switch whose contacts c_4 thereupon close and cut out a resistance section r_3 from the field circuit of the motor M_1 to give a decreased speed during hoisting, and the other of said circuits energising the winding w_5 of a relay having contacts l_{c5} which close energising the winding B_r of an electromagnetic brake for operating the same to its released position. All these three circuits established at the first notch are completed through an interlock $4c_1$ on the main switch winding w_1 , so that they will all be de-energised upon the occurrence of overload.

The motor M_1 accordingly starts in the hoist direction at slow speed.

At the second hoisting notch h_2 , an energising circuit is established through drum contact 4 for the winding w_6 of a first resistance-removing contactor whose contacts l_{c6} thereupon close, cutting out the first resistance section of the generator field circuit, and the motor speeded up. At the third hoisting notch h_3 , an energising circuit is established through drum contact 5 for the winding w_7 of the second resistance-removing contactor, whose contacts l_{c7} thereupon close cutting out a second resistance section of the resistance R . At the fourth hoisting notch h_4 , an energising circuit is established through drum contact 6 for the winding w_8 of the third resistance-removing contactor whose contacts l_{c8} close, cutting out a third section of resistance R ; and at the fifth hoisting notch h_5 an energising circuit is established through drum contact 7 for winding w_9 of the fourth resistance-removing contactor whose contacts l_{c9} close, cutting out a fourth section of resistance R . At said fifth hoisting notch an energising circuit is also established through drum contact 8 , for the winding w_{10} of the fifth and last resistance-removing contactor whose contacts l_{c10} close removing the fifth and last section of resistance R , but this must be subsequently to the preceding circuit as will hereinafter appear. All the resistance is now cut out of the generator field GF_1 .

Finally at the sixth hoisting notch h_6 , an energising circuit is established through drum contact 9 for the winding w_{11} of a normally closed accelerating switch, whose contacts c_{11} open inserting resistance r_1 in the circuit of the motor field MF_1 and the motor still further speeded up.

At the second notch h_2 , an auxiliary contact $2c_6$ on the winding w_6 of the first resistance-removing contactor establishes, through the aforesaid auxiliary contact $2c_3$ on the hoist switch, and independently of the drum D_1 , the three circuits (through windings w_3 , w_4 and w_5 respectively) which were established at the first notch. At the third notch h_3 an auxiliary contact $2c_7$ on the winding w_7 of the second resistance-removing contactor establishes, independently of the drum D_1 , the circuit through the winding w_6 which was established at the second notch. At the fourth notch h_4 an auxiliary contact $2c_8$ on the winding w_8 of the third resistance-removing contactor establishes, independently of the drum D_1 , the circuit through the winding w_7 which was established at the third notch. At the fifth notch h_5 an auxiliary contact $2c_9$ on the winding w_9 of the fourth resistance-removing contactor establishes independently of the drum D_1 the circuit through the winding w_8 which was established at the fourth notch. At the fifth notch also, an auxiliary con-

tact $2c_{10}$ on the winding w_{10} of the fifth resistance-removing contactor establishes, independently of the drum D_1 , the circuit through the winding w_9 which was also established at the fifth notch. Finally at the sixth notch h_6 an auxiliary contact $2c_{11}$ on the winding w_{11} of the said normally closed accelerating switch establishes, independently of the drum D_1 , the circuit through the winding w_{10} which was established at the fifth notch. The provision of these auxiliary contacts $2c_6$ to $2c_{11}$ as will hereinafter appear, prevents insertion of the resistance sections too fast when the drum is returned to the normal position.

Throughout the whole of the preceding operation, if the handle of the drum D_1 is thrown right over, the circuit established at any notch after the first, can only be established a time interval after the circuit or circuits established at the preceding notch. Thus, each resistance-removing contactor is provided with a hold-out coil $1w_6$ to $1w_{10}$ in series with its closing coil w_6 to w_{10} . The hold out coils $1w_7$ to $1w_{10}$ are respectively short circuited by normally open auxiliary contacts $3c_6$ to $3c_9$ on the preceding resistance-removing contactor. The first hold out coil $1w_6$ is short circuited by normally open contacts $2c_5$ on the winding of the brake controlling relay w_5 . If the handle is thrown quickly over through the several notches, each hold out coil $1w_6$ to $1w_{10}$ will receive current before the auxiliary contact $2c_5$ or $3c_6$ to $3c_9$ on the preceding contactor has had time to short circuit it and, until the current in this hold-out coil has died away, the contactor cannot close. Any other form of timing means may be provided for this purpose.

It will be observed that the winding w_{11} of the accelerating switch for inserting resistance in the motor field MF_1 cannot be energised until after closure of auxiliary contacts $3c_{10}$ on the winding w_{10} .

The aforesaid auxiliary contacts $2c_6$ to $2c_{11}$ for preventing the sections of the resistance R from being inserted too fast when the drum D_1 is being returned to the normal position, operate, as will be understood, by causing the contactors l_{c10} to l_{c6} to open consecutively in the reverse order to that in which they closed; and, furthermore, each contactor takes a time interval to open as its winding w_{10} to w_6 is shunted by a resistance r_{10} to r_6 , and its current therefore takes a time to die away after its circuit is disconnected. This resistance should be suitably proportioned to the spring tension on the contactor to obtain the necessary time intervals between the falling out of the contactors.

The operation of the holding-line drum D_1 in the lowering direction is the same as in the hoisting direction except that the generator field GF_1 is energised in the reverse direction and neither the normally open decelerating contacts c_4 nor the normally closed accelerating contacts c_{11} come into operation, so that the general speed is faster in the lowering direction but the final increase in speed is dispensed with. Thus at the first notch h_1 a lowering switch has its winding w_{12} energised through drum contact 10 , thereby closing contacts l_{c12} and effecting energisation of the generator field GF_1 in the lowering instead of the hoisting direction, and the auxiliary contact $2c_{12}$ on the lowering switch does not, as in the case of $2c_3$ on the hoisting switch, establish an energising circuit for the winding w_4 of the normally open decelerating contacts c_4 .

Said contacts 2c12, however, function in analogous manner to the contacts 2c3 to maintain the circuits of the lowering switch winding w12 and of the brake relay winding w5.

In all other respects, save that the sixth lowering notch is dispensed with, the operation in the lowering direction is precisely the same, through notches 12 to 15, as in the hoisting direction as will be clear from the drawing.

The closing line drum D2 is exactly the same as the holding line drum D1 except that the sixth notch, at which the normally closed accelerating switch is energised, is dispensed with in the hoisting direction and is added in the lowering direction, and except that a jamming relay, whose operation will be described is provided, said jamming relay having normally closed contacts jrc connected between the line L2 and all the contactor windings after w1 and having its winding jrw connected in the motor generator circuit. Thus, in the case of the closing line, the general speed as in the case of the holding line, is faster in the lowering direction, but contrariwise to the holding line, there may be a final increase in speed in the lowering direction but not in the hoisting direction.

It has therefore been deemed clearer not to append any further reference to Figure 4 save to show that there are six lowering notches 11 to 16 and only five hoisting notches h1 to h5. It is deemed that the operation of the drum D2 will be clear from the preceding description of that of D1.

In operation therefore, when it is desired to hoist with a full grab, making both motors M1 and M2 share the load, both drums D1 and D2 are moved together, notch by notch, in the hoisting direction, the sixth notch h6 on the holding line drum D1 not being used. The motors M1 and M2 will thus run at the same rate sharing the load equally.

For hoisting the open grab, the holding line drum D1, whose motor M1 must take the whole of the load, is moved one notch in advance of the closing line drum D2 right up to the full speed position, the sixth notch h6 on said holding line drum accordingly coming into use. Thus, the holding line motor M1, although under load, will move at least as fast as the closing line motor M2 which is running light, and there will be no danger of the closing line picking up the load and closing the grab.

When lowering the open grab, the closing line drum D2 is moved one notch in advance of the holding line drum D1, and this, although the holding line motor M1 which must take the whole of the weight, will be pulled round at somewhat above its unloaded speed, the closing line motor M2 will move at least as fast as said holding line motor and there will be no danger of the closing line picking up the load and closing the grab. In this case the sixth notch 16 of the closing line drum D2 in the lowering direction will come into use. Finally, for lowering the full grab both drums D1 and D2 are moved together in the lowering direction, notch by notch, and the motors M1 and M2 will rotate at the same rate, sharing the load. In this case the sixth notch 16 of the closing line drum D2 in the lowering direction will not come into use.

The two drums D1 and D2 are arranged as shown in Fig. 5, so that their handles may be grasped when necessary by one hand so as to facilitate moving them together.

Safety latches, controlled by windings w13 and w14 respectively in parallel with the windings w3 and w12 of the hoisting and lowering switches, are provided for preventing reversal of the drum, while the hoisting or lowering switch, as the case may be, is closed.

The aforesaid jamming relay jrw, jrc is for the purpose of safeguarding the mechanical parts of the hoist. If for example the grab should close upon a fixed part, the closing line would become sufficiently overloaded for the contacts jrc to open thereby ensuring de-energisation of all the contactor windings after w1. Thus the pull on the holding line will exceed that on the closing line and the grab will open.

Each generator is provided with a so called "suicide" circuit. That is to say the generator field is normally connected, through suitable resistances r11 and r12, across the generator armature, through normally closed auxiliary contacts 3c3 and 3c12 on the windings w3 and w12 of the hoist and lowering switches. During hoisting and lowering one or other of these auxiliary contacts will be open and the "suicide" circuit will therefore be interrupted, but, when the drum is returned to zero, said "suicide" circuit is established and the field is connected across the armature in such a sense as to be quickly demagnetised.

The lines L1, L2 may be supplied from any constant voltage direct current source such as a small exciter.

What I claim and desire to secure by Letters Patent is:

1. The combination with a grab bucket having a holding line and a closing line, of a motor for operating each of said lines, separate generators for supplying current to the armatures of said motors, separate controllers for controlling the fields of said generators to selectively control the direction of operation of said motors and also the speed thereof, said controllers being operable to subject the armatures of said motors to the full voltage of their associated generators for operation of said motors at corresponding speeds in hoisting or lowering direction with the weight of the grab bucket shared by said holding and closing lines and means associated with said controllers for selectively controlling the field strength of said motors while subjecting the armatures of said motors to the full voltage of their associated generators to provide for operation of said motors in hoisting or in lowering direction at corresponding speeds with substantially the entire weight of the grab bucket supported by said holding line.

2. The combination with a grab bucket having a holding line and a closing line, of a motor for operating each of said lines, separate generators for supplying current to the armatures of said motors, separate controllers for controlling the fields of said generators to selectively control the direction of operation of said motors and also the speed thereof, said controllers being operable to subject the armatures of said motors to the full voltage of their associated generators for operation of said motors at corresponding speeds in hoisting or in lowering direction with the weight of the grab bucket shared by said holding and closing lines, means associated with the controller for said holding line generator for weakening the field of the holding line motor while maintaining full generator voltage for operation of said holding line motor in hoisting direction, said means enabling hoisting opera-

tion of both of said motors at a corresponding high speed with substantially the entire weight of the grab bucket supported by said holding line.

3. The combination with a grab bucket having a holding line and a closing line, of a motor for operating each of said lines, separate generators for supplying current to the armatures of said motors, separate controllers for controlling the fields of said generators to selectively control the direction of operation of said motors and also the speed thereof, said controllers being operable to subject the armatures of said motors to the full voltage of their associated generators for operation of said motors at corresponding speeds in hoisting or in lowering direction with the weight of the grab bucket shared by said holding and closing lines and means associated with the controller for said closing line generator for weakening the field of the closing line motor while subjecting the armature of said closing line motor to full generator voltage for operation of said closing line motor in lowering direction, said means enabling lowering operation of both of said motors at a correspondingly high speed with substantially the entire weight of the grab bucket supported by said holding line.

4. The combination with a grab bucket having a holding line and a closing line, of a motor for operating each of said lines, separate generators for supplying current to the armatures of said motors, separate controllers for controlling the fields of said generators to selectively control the direction of operation of said motors and also the speed thereof, each of said controllers including a master switch movable in opposite directions out of an intermediate off position to select the direction and speed of operation of its associated motor and said master switches having corresponding hoisting and lowering positions wherein the armatures of said motors are 40

subjected to the full voltage of said associated generators, field weakening means for each of said motors and means associated with said master switches for selectively controlling said field weakening means while subjecting the armatures of said motors to the full voltage of their associated generators to provide for operation of said motors in hoisting or in lowering direction at corresponding speeds with substantially the entire weight of the grab bucket supported by said holding line.

5. The combination with a grab bucket having a holding line and a closing line, of a motor for operating each of said lines, separate generators for supplying current to the armatures of said motors, separate controllers for controlling the fields of said generators to selectively control the direction of operation of said motors and also the speed thereof, each of said controllers including a master switch movable in opposite directions out of an intermediate off position to select the direction and speed of operation of its associated motor and said master switches having corresponding hoisting and lowering positions for subjecting the armatures of said motors to the full voltage of their associated generators, means associated with said master switches for selectively weakening the fields of said motors while subjecting the armatures of said motors to the full voltage of their associated generators to provide for operation of said motors in hoisting or in lowering direction at corresponding speeds with substantially the entire weight of the grab bucket supported by said holding line and a switch responsive to overload conditions in the armature circuit of the motor associated with said closing line for weakening the field of the generator associated with said closing line motor.

JOHN RUSSELL TAYLOR.
